Primary Examiner — John R Yeh(74) *Attorney, Agent, or Firm* — Olive Law Group, PLLC(57) **CLAIM**

The ornamental design for a mop scraper, as shown and described.

DESCRIPTION

FIG. 1 is a top, front and right side perspective view of a mop scraper showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the portion labeled "9" framed in FIG. 1;

FIG. 10 is an enlarged view of the portion labeled "10" framed in FIG. 1;

FIG. 11 is an enlarged view of the portion labeled "11" framed in FIG. 1;

FIG. 12 is an enlarged view of the portion labeled "12" framed in FIG. 2;

FIG. 13 is an enlarged view of the portion labeled "13" framed in FIG. 2; and,

FIG. 14 is an enlarged view of the portion labeled "14" framed in FIG. 3.

In FIGS. 1-3 and FIGS. 9-14, a dot dash-line rectangular frame defines the boundary of an enlarged view and form no part of the claimed design.
